UNITED STATES PATENT OFFICE.

FRANK H. WEIMER, OF NOGALES, ARIZONA.

COMBINED AUTOMATIC AND STRAIGHT AIR VALVE MECHANISM.

1,262,883.

Specification of Letters Patent. Patented Apr. 16, 1918.

Application filed March 14, 1917. Serial No. 154,690.

To all whom it may concern:

Be it known that I, FRANK H. WEIMER, a citizen of the United States, residing at Nogales, in the county of Santa Cruz and State 5 of Arizona, have invented certain new and useful Improvements in Combined Automatic and Straight Air Valve Mechanisms, of which the following is a specification.

My invention relates to combined automatic and straight air valve mechanisms, and more particularly to those designed for use on railroad cars and locomotives and operated by compressed air, either automatically by a reduction of the air in the train- 10 pipe system, utilizing the auxiliary air-pressure in the well-known manner, or by increasing the normal train-pipe pressure, employing straight air from the main reservoir of the locomotive direct to the brake-cylinder. 15

One of the objects of my invention is to provide a valve mechanism which will set the brakes, through the instrumentality of compressed air direct from the main reservoir 20 of the locomotive, by an increase in the normal train-pipe pressure, and at the same time providing a mechanism which will set the brakes automatically, through the instrumentality of the auxiliary reservoir air-pressure in the well-known manner, in the 25 event of a break in the train-pipe or hose.

A further object of my invention is to provide a valve mechanism particularly adapted to the interchange of traffic, in that 30 the straight-air passage or port can be closed by a plug-valve and the automatic passage or port opened by another plug-valve, thus providing a first-class automatic valve, and when a sufficient number of cars equipped 35 with my device to make up a train can be assembled the automatic passage or port can be closed and the straight-air passage or port opened, thus enabling the engineer to run the train by the employment of straight 40 air only, which is safest and in many ways the most satisfactory.

A still further object of my invention is to provide an improved, positive-acting, automatic and straight-air valve whereby the 45 brakes may be applied, held, and released at the will of the engineer, who can apply the brakes by the use of straight air, and which will apply the brakes automatically in the event of a break in the train-pipe or 50 hose.

A still further object of my invention is

to provide a valve which is simple, inexpensive, and durable in construction, and easy and effective in operation.

My invention consists in the several features, and in the construction, combination, and arrangement of the features, as will be more fully hereinafter described and claimed.

Referring to the drawings, Figure 1 is a 60 longitudinal, sectional view, showing the several parts of the valve in the relative positions they assume when the straight air application is made or on automatic release in extreme innermost position; Fig. 2, a longitudinal sectional view, showing the several parts of the valve in the relative positions they assume when the valve is in lap or holding position in both automatic and straight air applications; Fig. 3, a longitudinal 65 sectional view, showing the several parts of the valve in the relative positions they assume when released on straight air reductions or when applying the brakes with automatic air in service applications; Fig. 4 70 a longitudinal sectional view, showing the several parts of the valve in the relative positions they assume in emergencies; Fig. 5, an enlarged view of the choking device located in the upper part of the casing; Fig. 75 6, a cross-sectional view of the slide-valve, showing the position it assumes when straight air, automatic air, and straight and automatic emergencies are being applied; Fig. 7, a cross-sectional view of the slide- 80 valve, showing the same in release position on both automatic and straight air applications; Fig. 8, a bottom plan view of the slide-valve; Fig. 9, a top view of the slide-valve seat in the casing; Fig. 10, a side view 85 of the piston and slide-valve; and Fig. 11, a cross-section on the line X X of Fig. 10.

In the drawings, in which similar reference characters denote corresponding parts throughout the several views, 1 represents 90 the inclosing casing of the valve, made preferably of two hollow parts 2 and 3, secured together by means of bolts 4, and provided with a screw-cap 5 at the outer end and a screw adjusting plug 6 at the other end, and 95 having a plurality of air-holes or apertures 7. The hollow portion 3 of the casing is provided with a spiral spring 8, seated at its inner end in a slidable flanged cap 9, its outer end abutting against a screw-plug 10, 100 which is adapted to be adjusted in order to 105 regulate the tension of the spiral spring 8.

The hollow part 2 of the casing is provided with a flanged cap 11 at its outer end, said cap 11 being provided with a plurality of air-holes or apertures 12 and being normally seated against the shoulder 13 in the part 2 of the casing and held against said shoulder by means of a spiral spring 14. In the upper portion of part 2 of the casing an angular by-pass 15 is provided for the passage of air from part 3 to part 2 of the casing. A piston-cavity 16 is provided in the inclosing casing 1, and in the upper part of the said cavity is located a seepage-groove 17, adapted to be open when the valve is in lap position, Fig. 2, but closed when the valve is in the position illustrated in Fig. 3 of the drawings.

A manually-operated set-screw 18 is provided to regulate the size of the angular by-pass 15, and 19 is a choking device located in the upper part of part 2 of the casing, (see Fig. 5,) consisting of a plunger 20, mounted in the bore 21 in the part of casing 2, a threaded collar 22, a pin 23, and a coil-spring 24. The pin 23 abuts against the threaded collar 22 at all times except when the piston 25 is at its most forward position, while the coil-spring 24 holds the plunger normally out of the angular by-pass 15 when not in use.

At the lower portion of the inclosing casing 1 a by-pass 26 is located, formed between parts 2 and 3 of the said casing 1, which said by-pass communicates directly with the train pipe or hose (not shown). A horizontal port 27 is provided in the lower part of part 2 of the casing for the passage of air to and from the brake-cylinder (not shown), which said port 27 communicates with the vertical port 28. A plug-valve 29^a is provided in the vertical port 28 to close the same when desired. The vertical port 29 also communicates with the horizontal port 27 and is provided with a plug-valve 30 for closing the same when desired.

An exhaust-port 31 is provided to be operated with the port 29 when straight air exhaust is employed, and an exhaust-port 32 is provided to be operated with the port 28 when automatic exhaust is employed.

A piston 25 is mounted in the casing 1, consisting of a head 33, slidably mounted in chamber 16, and a piston-rod 35, mounted in part 2 of the casing 1, having a flange 55 at one end, and scalloped, as at 37, to permit the passage of air, (see Fig. 10,) and the other end being secured to piston-head 33 by a nut 38, and having located within the end a bore 39. Within the bore 39 is located 60 a stud 40, the said stud being held in its normal position by a coil-spring 41 and a washer 42.

A slide-valve 43, of rectangular shape, is provided, being shouldered into the lower 65 side of piston-rod 35. In the slide-valve 43

is provided a port 44, adapted to register with port 29 in part 2 of the casing; also, a port 45, adapted to register with ports 28, 29, 31 and 32 in part 2 of the casing, and a port 46, adapted to register with port 28 in part 2 of the casing 1. The slide-valve 43 is also provided with a port 47, adapted to register with port 28, in automatic emergency position.

To operate my valve by the application of straight air, the plug-valve 30 will be opened and the automatic port 28 will be closed with the plug-valve 29^a, as shown in Fig. 1. The engineer increases the normal train-pipe pressure in the usual manner and this increased pressure passes through by-pass 26 and into the piston-chamber 16 forcing the piston-head 33 forward and compressing spring 14, and uncovering by-pass 15 in the piston-chamber 16, allowing this increased pressure to flow into the valve-chamber 48, said valve-chamber being always in communication with the auxiliary reservoir, not shown, through air-holes or apertures 12, 37 and 7 which are always open for the passage of air.

The auxiliary reservoir is kept constantly charged with the normal train-pipe air pressure when straight air is employed. When the piston 25 is moved forward, the slide-valve 43 also moves forward, and port 44 therein is made to register with port 29 in the part 2 of casing 1, thereby opening communication between the train-pipe and the brake-cylinder, (see Fig. 1). With an increased train-pipe and piston-chamber pressure and a normal pressure in the valve-chamber 48 and the auxiliary reservoir, a certain increased pressure of air will enter the valve-chamber 48 and auxiliary reservoir, and the normal pressure of air will go out into the brake-cylinder, holding the auxiliary reservoir to normal train-pipe pressure. When more air can enter the valve-chamber 48 than can escape into the 110 brake-cylinder, said chamber would soon become charged with the same pressure as the train-pipe, when the spring 14 would throw the valve into lap, to avoid this possibility a set-screw 18 has been provided in 115 the casing 2, said set-screw being adapted to enter the angular by-pass 15 to choke the passage, as desired, for the purpose of regulating the by-pass 15 to the end that the pressure in the valve-chamber 48 may be held at normal train-pipe pressure during a straight-air application. At the time of a straight-air application or an automatic release the valve is constructed in such a manner that with a heavy pressure spring 14 will be compressed and permit the ports to slightly overlap while with less pressure they will remain open, but as no more air should be permitted to enter the valve-chamber 48 than can escape, the choking device 120

125 14 will be compressed and permit the ports to slightly overlap while with less pressure they will remain open, but as no more air should be permitted to enter the valve-chamber 48 than can escape, the choking device 130

- 19, (Fig. 5,) has been provided to throttle the by-pass 15 to the same extent that ports 29 and 28 are throttled to the end that the pressure in the auxiliary reservoir may be held to normal at all times. When the ports 29 and 28 communicating with the brake-cylinder, are open, the angular by-pass 15 will be open, but when the piston 25 and slide-valve 43 is moved beyond the ports 29 and 28 choking them partially, the piston-head 33 compresses the coil-spring 24 and forces the plunger 20 into the by-pass 15. This device is employed in order to prevent a too strong setting of the brakes on the forward cars of a train at the beginning of an application, when straight air is utilized. It also chokes the automatic release on the rearward cars of a train with the attending advantages.
- 20 When the engineer has sufficient air-pressure on the brakes, he places his valve in lap, cutting off further entrance of air into the train-pipe. Then the increased train-pipe pressure will find its way into the brake-cylinders until equalization between the piston-chamber 16 and the valve-chamber 48 takes place, when spring 14 will force the piston 25 and the slide-valve 43 back to lap position, closing all ports. (See Fig. 2.)
- 21 When the angular by-pass 15 is closed, the seepage-groove 17 is open to permit the passage of a little air in the event of a leakage and to keep the auxiliary reservoir charged with the normal train-pipe pressure. When the engineer desires to release the brakes, he reduces the train-pipe pressure, causing the piston 33 to move backward against spring 8, and ports 29 and 31 will be in communication, through cavity 45, exhausting the brake-cylinder and leaving the auxiliary reservoir charged with the normal train-pipe air-pressure.
- 22 My device is so constructed that in the full release position the end of stud 40, located in the end of piston 25, will contact with the slideable flanged cap 9, in a certain reduction forcing the coil-spring 41 behind stud 40, permitting the piston to travel backwardly far enough to cause cavity 45 to slightly overlap ports 29 and 31 on the forward cars of a train. In the rearward cars of a train, where the reduction is less forceful, the spring 41 will not be compressed and the ports 29 and 31 will remain entirely open. When the train-pipe pressure equalizes all ports will be open. This construction tends to avoid pulling the train apart. The spring 8 is made strong enough to resist about 20 pounds reduction.
- 23 In the event of a break in the train-pipe or hose, when operated with automatic air, the piston 33 is forced back to the extreme position, forcing the spring 8 and providing a communication between the auxiliary reservoir and the brake-cylinder through ports 29 and 46 (see Fig. 4,) which will reduce the air-pressure in the auxiliary reservoir to about 50 pounds, which will suffice to keep spring 8 forced back and retain air in the brake-cylinders.
- 24 When it is desired to use my valve as an automatic valve, the straight-air port 29 is closed by plug-valve 30, and the automatic port 28 is opened by plug-valve 29a. Then the valve will work in conjunction with the automatic valves in general use. To set the brakes, the engineer reduces the train-pipe pressure, as usual, and piston 33 moves backwardly, connecting ports 28 and 46, through which air passes from the auxiliary reservoir to the brake-cylinder. After some air has passed to the brake-cylinder the air pressure in valve-cavity 48 will be somewhat reduced and the slide-valve will be pushed back to lap by the train-pipe pressure. At the same time the spring 41 is compressed on the forward cars of a train, causing ports 28 and 46 to overlap and restrict the passage of the air, while on the rearward cars of the train the said spring 41 is not compressed and the ports 28 and 46 are not choked. This prevents the bumping of the forward cars by those at the rear of a train.
- 25 In the event that the engineer desires to apply emergency, the piston 33 will move still farther back, forcing the spring 8 and connecting ports 28 and 47, (Fig. 4). After equalization takes place between the auxiliary reservoir and the brake-cylinder, spring 8 will move slide-valve 43 back to service position unless the engineer drains the pipe.
- 26 To release the brakes the engineer increases the train-pipe pressure forcing the piston 33 forward and ports 28 and 32 will be connected by cavity 45 and exhaust the brake-cylinder, at the same time compressing spring 14 more on the forward cars of a train than on the rear cars, where the pressure is less, retarding the release on the forward cars of the train, with the attending advantages. While release is being effected, train-pipe air is charging the auxiliary reservoir, and when normal train-pipe air is equalized in the auxiliary reservoir spring 14 forces the piston back to lap, closing all ports after release is completed. The seepage-groove 17, however, is open at this time, giving assurance that the auxiliary reservoir is charged at all times with the normal train-pipe pressure.
- 27 When the normal train-pipe pressure is raised a stated number of pounds above normal, and the increased pressure flows into the valve-chamber 48 through the angular by-pass 15, when the normal auxiliary reservoir pressure flows through ports 44 and 29 into the brake-cylinder, it will be noted that if the passages for the entrance and

exists of the air are of the same capacity the auxiliary reservoir will remain at normal. When the engineer has sufficient air in the brake-cylinder, he moves his valve to lap, 5 closing all ports. Thus when the increased pressure that has been supplied from the train-pipe has passed into the brake-cylinders and spring 14 has pressed the slide-valve 43 back to the lap position, (Fig. 2) 10 leaving the auxiliary reservoir and train pipe pressure at normal it will be noted that the brakes have been set with the increased pressure supplied through the train-pipe, the pressure in the brake-cylinders depending 15 entirely on the amount of overcharge utilized, and if the first operation is not successful, the engineer is in position to repeat the same.

I do not wish to be understood as limiting 20 myself to the specific details of construction as shown and described, as the same may be modified without departing from the spirit or scope of my invention.

Having thus described my invention, what 25 I claim is—

1. In an air-brake system, a piston, a piston-chamber having a compressed air chamber communicating therewith, a valve-chamber, a valve, a by-pass passage forming a 30 communication between said piston and valve-chambers, means for restricting or controlling the passage of air through said by-pass passage adapted to be operated by means of the said piston.

2. In an air-brake system, a piston-chamber having a piston therein, a valve-chamber having a slide-valve therein, a by-pass forming a communication between said chambers, and means in said piston-chamber 40 adapted to equalize the air-pressure in said chambers.

3. In an air-brake system, a compressed-air chamber, a piston-chamber, a piston in said chamber, a valve-chamber, a valve in 45 said chamber connected to said piston, a by-pass port between said compressed-air chamber and the piston-chamber, a by-pass port between said piston-chamber and said valve-chamber, and a spring-operated plunger 50 valve adapted to control the amount of air passing through the by-port.

4. In an air-brake system, a compressed air chamber, a piston-chamber, a piston in

said chamber, a valve-chamber having an air-seepage groove, a valve in said chamber, 55 a by-pass port adapted to form a communication between the compressed-air chamber and the piston-chamber, the piston-chamber and the valve-chamber being in open connection with each other, a valve in the by-pass port between the piston and valve chamber adapted to be moved in one direction by a spring for the purpose of controlling 60 the amount of air passing therethrough from the piston-chamber to the valve-chamber. 65

5. In an air-brake system, a valve-chamber, an air-inlet, an exhaust, a valve, means for adjusting the size of the air-inlet of the valve-chamber in order to regulate said air-inlet with respect to the port exhausting therefrom.

6. In an air-brake system, a casing, a compressed-air chamber, a piston-chamber, a piston in said chamber, a valve-chamber, a valve in said chamber, a by-pass port forming a communication between the piston and the valve chambers, a valve for controlling the amount of air passing through said by-pass seated in a socket in said casing and 75 provided with a spring, said spring adapted to cause said valve to be projected normally into the piston-chamber and said piston adapted to cause said valve to be projected into the by-pass between the piston and valve chambers and to control the amount of air passing through said by-port from the piston 80 to the valve chamber. 85

7. In an air-brake system, a casing having 90 ports, a compressed-air reservoir, a piston-chamber having an air-seepage groove, a piston in said chamber, a valve-chamber, a slide-valve therein having ports adapted to register only with the ports of the said casing, a by-pass port forming a communication 95 between the piston and valve chambers, and a valve to control the amount of air passing through said by-pass into the valve-chamber and adapted to be operated by means of the said piston. 100

In testimony whereof I affix my signature in the presence of two witnesses.

FRANK H. WEIMER.
